SCREW FEED AND DRIVE MECHANISM

Ernest H. Shaff, Hamilton, Ind., assignor to Keller
Tool Company, Grand Haven, Mich., a corpo-
ration of Michigan

Application January 3, 1951, Serial No. 204,127

11 Claims. (Cl. 144—32)

1

The invention relates to a feed or delivery mechanism for screws and like elements, hereinafter referred to for convenience as screws, and especially adapted for use with power operated tools so as to expedite the application of the screws to the work.

A general object of the invention is to provide an improved feeding mechanism of the character set forth in which the delivery of screws to a desired holder is utilized to govern the operation of the mechanism in feeding additional screws to such holder.

Another object is to provide a feeding and delivery mechanism wherein as an incident to the disassociation of one screw from a holder another screw is delivered thereto.

A more specific object is to provide a screw feeding or delivery mechanism associated directly with a driving tool having a finder constituting the screw holder to which the screws are delivered successively.

The objects of the invention thus generally set forth together with other objects and ancillary advantages are attained by the construction and arrangement shown by way of illustration in the accompanying drawing, in which:

Figure 1 is a fragmentary elevational view of a pneumatic screw driver embodying the features of the present invention, with certain portions broken away and shown in vertical section.

Fig. 2 is a fragmentary vertical section of the forward end portion of the tool shown in Fig. 1.

Fig. 3 is a fragmentary side elevation partly in section of the forward end of the tool illustrated in Fig. 1 but showing the relative positions of elements of the tool when a screw is being driven.

Fig. 4 is a transverse section substantially in the plane of line 4—4 of Fig. 1.

Fig. 5 is a side elevation on an enlarged scale of an aspirator element of the tool shown in Fig. 1.

While the invention is susceptible of various modifications and alternative constructions, there is shown in the drawing and will herein be described in detail the preferred embodiment, but it is to be understood that it is not thereby intended to limit the invention to the form disclosed, but it is intended to cover all modifications and alternative constructions falling within the spirit and scope of the invention as expressed in the appended claims.

In the present embodiment of the invention, the improved feed mechanism is directly associated with a portable pressure fluid actuated screw driver comprising an elongated cylindrical hous-

2

ing 8 having a rotary motor 9 therein for driving a spindle 10 through the medium of a combined speed reduction gearing and clutch mechanism generally indicated at 11. The spindle 10 is journaled in a barrel 12 rigid with the forward end of the main housing 8. The spindle has a bore 14 extending axially therethrough in the forward end of which is received the shank of a screw driver bit 15.

10 Pressure fluid, such as compressed air, is supplied to drive the motor 9 by way of a supply pipe 16 which is connected to the tool by means of a fitting 17. The latter is received in a head 18 which, in turn, serves to close the rear end of 15 the main housing 8. Pressure fluid thus supplied is under the control of a throttle valve generally indicated at 19 in the tool head 18 which is adapted to be operated by a lever 20. As shown, the lever 20 extends along one side of the main housing 8 in position for convenient manipulation by the fingers of an operator using the tool. From the valve 19, pressure fluid is conducted to the motor 9 by way of an annular supply chamber 21 surrounding the valve 19 and a supply passage 22.

In accordance with the present invention, means is provided for successively conveying screws from a hopper or other supply source to a suitable holder, which means includes a release mechanism operative in response to disassociation of a delivered screw with respect to the holder to release another screw from the hopper. While the holder may take various forms, in the present embodiment it is directly associated with the tool and constitutes a finder 25 mounted on the nose of the tool and serving to hold a screw in position for engagement by the bit 15 so that it can be applied to a workpiece.

The finder, as shown, includes a cylindrical body portion 26 which is telescopingly received in the forward end of the barrel 12. The finder 25 and the barrel 12 are constrained to relative longitudinal movement by means of a screw 27 carried by the barrel 12 and received in an elongated slot 27A formed in the body portion 26 of the finder 25 adjacent its upper end.

Retaining means for a screw 28 is provided at the outer end of the finder 25. In the present instance this means includes a set of three fingers 28 resiliently mounted to releasably hold a screw therebetween. The fingers 28 are received in respective ones of a peripherally spaced series of longitudinally disposed grooves 29 formed adjacent the outer end of the body portion 26. The grooves 29 intersect radial slots 30, at the

outer end of the body portion 26 of the finder, and the tapered tips 28a of the fingers 28 extend therethrough into the body portion 26 for engagement with the threaded body of the screw S1 so as to firmly retain the screw in position in the finder for application to the work. To prevent longitudinal movement of the fingers with respect to the body 26 each finger is provided with a laterally projecting lug 28b which is received in a recess 31 in the body portion 26 at the upper end of each of the grooves 29.

The fingers 28 are held in place on the finder by a snap ring 32 which surrounds the body portion 26 of the finder and is received in a transverse groove adjacent the inner end of each of the fingers 28. This construction and arrangement permits the fingers to spread radially outward so as to receive a screw therebetween.

In use, the tool is moved so that the screw S1 is brought into desired position on a workpiece 20 and upon exerting a slight force in a direction to press the tool against the work the finder 25 is telescoped within the barrel 12 and the bit 15 is moved into engagement with the head of the screw S1. Thereafter, the clutch 11 is engaged so that upon admission of pressure fluid to actuate the tool, the screw S1 is driven.

In the exemplary form of the invention, aspirator means in conjunction with an escapement mechanism is utilized to successively withdraw screws from a hopper H and to direct them to the finder 25 in position to be driven by the bit 15. As shown, the aspirator means, generally designated 35, includes a tubular element 36 screw threaded into the enlarged upper end of a stepped bore 38 which extends longitudinally through a boss 39 formed integral with the tool head 18 and projecting laterally therefrom. The lower end of the bore 38 is of a diameter somewhat less than that of its upper end, and preferably the two ends of the bore 38 are joined by a tapered wall portion 40. Adjacent its inner end the tubular element 36 is of reduced diameter and at its inner end the element 36 also is tapered as at 36a.

This construction and arrangement defines an annular chamber 42 with a restricted annular outlet 43 to which the pressure fluid is supplied by way of a passage 44 in the tool head 18 from the valve chamber 21 upon actuation of the valve 19. Passage of pressure fluid from the chamber 42 and through its restricted outlet 43, by Venturi action, creates a suction or partial vacuum within the tubular element 36 which is transmitted by way of a flexible tube 45 to the escapement mechanism generally indicated at 46. Control of the Venturi action may be effected by varying the size of the annular orifice 43 between the tapered end of the element 36 of the tapered shoulder 40 in the bore 38. This can be accomplished simply by shifting the element 36 axially in the bore 38 by means of its screw threads. A locking nut 36A is provided to maintain the desired position of adjustment.

To join the tube 45 with the tubular element 36, the upper end of the latter is of enlarged internal diameter to receive the end of the tube 45. Also the upper end of the element 36 is slotted as at 47 and a clamping nut 48 is provided for coaction with the slotted end so as to form in effect a collet for gripping the end of the tube 45 to hold the same in place.

As shown, the escapement mechanism 46 includes a tube 50, a pawl 51 and an actuator 52 for the pawl. The tube 50 is of generally cy-

lindrical form having an inner diameter slightly larger than the diameter of the heads of the screws S. It is received in the outlet of the hopper H and to its outer end is secured the upper end of the tube 45.

The pawl 51 has two laterally extending fingers 51a and 51b which are spaced apart a distance substantially equal to the length of one of the screws S and which project into the tube 50 through openings 50a and 50b, respectively, therein. The pawl 51 is pivoted intermediate its ends on a lug 53 rigid with the tube 50 for rocking movement to alternately project the fingers 51a and 51b into the tube 50.

The actuator 52 for rocking the pawl 51 is of the pressure-responsive type and includes a push rod 54 connected at one end to the lower end of the pawl 51, and intermediate its ends the push rod is attached to a flexible diaphragm 56. The diaphragm 56 is disposed within a housing 58 and forms one side of a pressure chamber 59 within the housing. The housing 58 also has a bore 60 in the wall thereof opposite the diaphragm in which the other end of the push rod 54 is guidably received. Normally the pawl 51 and push rod 54 are maintained in a position such that the lower pawl finger 51b is projected through the opening 50b into the tube 50 in position to engage the head of the screw S2 and prevent it from dropping through the tubular element 50 into the tube 45.

Upon actuation of the valve 19 pressure fluid is admitted to the aspirator chamber 42 by way of the passage 44. By the Venturi action at the orifice 43 a partial vacuum is created which is transmitted to the pressure chamber 59 by way of the flexible tube 45, the tubular element 50 and a tube 51 which is connected at one end to the element 50 and at the other to the housing 58. By thus creating a partial vacuum within the chamber 59 the diaphragm 56 is moved inwardly. Such movement of the diaphragm retracts the push rod 54 and rocks the pawl 51 thereby withdrawing the finger 51b to permit the screw S2 to be drawn down the tubular element 50 and the tube 45. When the pawl 51 is rocked the finger 51a is projected into the tubular element 50 beneath the head of the screw S3 to prevent it from following its predecessor down the tube.

Received in the lower end of the bore 38 of the boss 39 of the tool head 18 is a tubular connecting member 62 the lower end of which is telescopingly received in a feeder tube 64. The latter is fixed at its lower end to the body portion 26 of the finder 25 adjacent the lower end thereof, and opens into it in angular relation. Interposed between the boss 39 and the upper end of the feeder tube 64 of the finder and disposed about the member 62 is an expansion spring 65 which serves to normally maintain the finder in outwardly telescoped relation with respect to the barrel 12 of the tube.

Pressure fluid from the orifice 43 is directed downwardly through the tubular element 62 and the feeder tube 64 and normally escapes through the open end of the body portion 26 of the finder 25. As previously described, the screw S2 is drawn downwardly through the flexible tube 45 and into the aspirator element 36 by the partial vacuum or suction created therein. Upon reaching the lower end of the aspirator element 36 the screw enters the stream of pressure fluid from the orifice 43 and is blown downwardly through the member 62 and the feeder tube 64 into body 70 26 of the finder 25 where its outer end engages

the tapered inner surfaces of the finger tips 28a and spreads the fingers 28 apart. The action of the snap ring 32 in pressing the fingers 28 inwardly results in gripping of the body of the screw. In this position, the screw head substantially blocks the escape of pressure fluid through the finder 25 thereby causing a pressure to be built up in the feeder tube 64, the tubular element 62, the aspirator element 36, the tube 45 and the tubular element 50. This pressure is also transmitted by way of the tube 61 to the pressure chamber 59 and the diaphragm 56 is returned to normal position. While this pressure and the inherent resilience of the diaphragm are ordinarily sufficient to move the diaphragm to normal position, a spring 66 is provided to insure such movement. The spring 66 is interposed between the diaphragm 56 and the housing 58 of the pawl actuator 52 and about the push rod 54. Upon return of the diaphragm 56 to normal position, the pawl finger 51a is withdrawn from the tubular element 50 and the finger 51b is extended thereto. This rocking of the pawl 51 releases the screw S3 permitting it to drop down into the position of the screw S2 shown in Fig. 1.

As long as a screw is in the position of the screw S1 in the outer end of the finder 25 as shown in Fig. 2 of the drawing, the pawl will be maintained in position wherein the finger 51b is extended, and succeeding screws will not be fed to the finder 25.

Upon completion of the driving of a screw by the tool the finder is withdrawn from the screw head. This opens the end of the finder relieving the pressure that built up in the feeder tube 64 and tubular element 62 and permits Venturi action to again obtain. This again creates the partial vacuum so as to actuate the escapement mechanism and supply another screw to the finder in position to be engaged by the bit 15 for application to a workpiece.

If desired, the tapered end 36a of the tubular element 36 may be provided with a circumferentially spaced series of angularly disposed slots or grooves 70, for the purpose of imparting a swirling motion to the stream of pressure fluid as it passes through the orifice 43. This produces an increase in the Venturi effect and thus increases the partial vacuum or suction created in the aspirator element 36, the tube 45 and escapement mechanism 46. By the same token, the velocity of the air in the tubular element 62 and feeder tube 64 will be similarly increased. The end result, therefore, is an increase in the speed with which the screws are fed from the hopper to the finder.

I claim as my invention:

1. In a pressure fluid actuated screw driver adapted to be connected to a pressure fluid source and to a hopper or the like containing a supply of screws, the combination comprising a finder for holding a screw in position for application to a workpiece and means for feeding screws one at a time to said finder, said means including a delivery passage interposed between the hopper and said finder, a pressure responsive escapement mechanism operatively associated with said passage to control the release of screws from said hopper to said passage, and an aspirator inserted in said passage and adapted for connection with the pressure fluid source for operation as an incident to the application of pressure fluid to actuate the screw driver for effecting a pressure change in said passage to actuate said mecha-

nism so as to release a screw for transmittal to the finder.

2. For use with a power actuated screw driver having a finder for holding a screw, means for feeding screws in position for reception in the finder, said means comprising, in combination, a hopper, a delivery passage connected with a source of air under pressure, an escapement mechanism responsive to variations in pressure in said passage to control the delivery of screws one at a time from said hopper into said passage, and means for actuating said escapement mechanism, said actuating means being pressure responsive and having connection with said passage so as to be operative as an incident to the removal of one screw from the finder to effect a decrease in pressure in said passage whereby to cause said mechanism to release another screw from said hopper.

3. In a pressure fluid actuated screw driver, the combination comprising a finder having connection with a source of pressure fluid, means defining a passageway for the reception of screws for delivery in position for reception in said finder, a pressure responsive escapement mechanism operatively connected with said passageway for controlling the delivery of screws one at a time therethrough and means providing a passage interconnecting said finder and said mechanism for transmitting the pressure change effected in said finder upon removal of one screw therefrom to actuate said mechanism whereby to release another screw for delivery through said passageway.

4. In a screw driver adapted to be connected to a source of compressed air for actuating the same and having a finder for holding a screw in position to be driven thereby, a screw feeding mechanism for supplying screws from a hopper to the finder, said mechanism comprising, in combination, a tube adapted to be connected between the finder and the hopper, release means adjacent the hopper end of said tube for controlling the discharge of screws one at a time from the hopper into the tube, an air operated actuator for said release means, and valve means for controlling the supply of compressed air to the screw driver and to said tube, said actuator being responsive to a drop in pressure in said tube upon removal of one screw from the finder to operate said release means so as to release another screw from the hopper for transmittal through said tube to the finder.

5. In a power driven screw driver adapted to be connected to a pressure fluid source and to a hopper containing a supply of screws to be driven thereby, the combination comprising a holder for retaining a screw, and a screw feeding mechanism associated with said holder and operable as an incident to the disassociation of a delivered screw with respect to the holder to supply another screw thereto, said mechanism including a tubular member connected between said holder and the hopper, an aspirator operatively associated with the pressure fluid supply to the screw driver and with said tubular member for creating the pressure differential in the latter, and means responsive to said pressure differential for releasing one screw at a time from said hopper for transmittal by way of said tubular member to said holder.

6. In a power driven screw driver adapted to be connected to a pressure fluid source and to a hopper containing a supply of screws to be driven thereby, the combination comprising a finder including a generally cylindrical body portion hav-

ing a series of peripherally spaced slots therein and fingers resiliently mounted in said slots for holding a screw in position to be driven by the screw driver, and a screw feeding mechanism associated with said finder and operable as an incident to the removal of one screw from the finder to supply another screw thereto in position to be driven, said mechanism including a tubular member connected between said finder and the hopper, an aspirator operatively associated with the pressure fluid supply to the screw driver and with said tubular member and operative to create a partial vacuum in the latter when said finder body portion is open and operative to create a positive pressure in said tubular member when said finder body portion is blocked by a screw, and means alternately responsive to said vacuum and positive pressure to control the release of screws from said hopper for transmittal by way of said tubular member to said finder.

7. For use with a screw driver having connection with a pressure fluid source to actuate the same and including a finder for holding a screw in position to be driven thereby, a screw feeding mechanism for supplying screws one at a time from a hopper to the finder, said mechanism comprising, in combination, a tube opening at one end into the finder and at the other end into said hopper, an aspirator interposed intermediate the ends of the tube and having connection with the pressure fluid source, a pressure responsive release means connected with said tube between said aspirator and the hopper, said aspirator being effective upon removal of a screw from the finder to produce a partial vacuum in the portion of said tube adjacent the hopper to actuate said release means so as to release another screw from the container and draw the same through the portion of said tube adjacent the container and the aspirator and thereafter blow the screw into said finder in position to be driven by the screw driver.

8. In a screw driver adapted to be connected to a source of compressed air to actuate the same and to a hopper or the like containing a supply of screws to be driven thereby, the combination comprising, a casing, an air motor within said casing, a bit driven by said motor, a tool head on one end of the casing, valve means including a supply chamber within said tool head for controlling the supply of compressed air to said motor, a finder on the other end of said casing disposed in telescoping relation to said bit and adapted to hold a screw in position to be driven by said bit, and screw feeding means for supplying screws one at a time for reception in the finder, said means including a pressure responsive escapement mechanism for controlling the release of screws from said hopper, and an aspirator communicating with said valve supply chamber and operative as an incident to the removal of one screw from said finder to actuate said pressure responsive means whereby to release another screw from said hopper.

9. In a screw driver adapted to be connected with a source of compressed air to actuate the same and with a hopper containing a supply of screws, the combination comprising a casing, an air motor within said casing, a bit driven by said motor, a tool head on one end of the casing, valve

means including a supply chamber within said tool head for controlling the supply of compressed air to said motor, a finder on the other end of said casing disposed in telescoping relation to said bit and adapted to hold a screw in position to be driven by said bit, and a screw feeding mechanism for supplying screws one at a time to the finder, said mechanism including a tubular element affording communication between the hopper and said finder, pressure responsive means operatively associated with said tubular element for releasing screws one at a time from the hopper, and means carried by the tool head and connected with said valve supply chamber and with said tubular element for effecting a pressure differential in the latter upon removal of one screw from said finder to actuate said pressure responsive means to release another screw from said container for delivery through said tubular element to said finder.

10. A pneumatic screw driver comprising, in combination, a casing, an air motor within said casing, a bit driven by said motor, a tool head closing one end of the casing and adapted to be connected with a source of compressed air, valve means including a supply chamber within said tool head for controlling the supply of compressed air to said motor, a finder on the other end of said casing disposed in telescoping relation to said bit and adapted to hold a screw in position to be driven by said bit, and a screw feeding mechanism for supplying screws one at a time to the finder, said mechanism comprising a hopper for a supply of screws, a tubular element affording communication between said hopper and said finder, pressure responsive means operatively associated with said tubular element for controlling the release of screws from said hopper, and means connected with said valve supply chamber and with said tubular element for effecting a pressure differential in the latter upon removal of one screw from said finder to actuate said pressure responsive means to release another screw from said container for delivery through said tubular element to said finder.

11. A mechanism for effecting the successive delivery of screws or like parts to a predetermined point, said mechanism comprising means defining a delivery passage communicating with a source of air under pressure, and a control device for effecting the movement of screws one at a time through said passage, said device including an element responsive to variations in pressure in the passage, and means affording communication between said element and said passage, said passage having a discharge portion dimensioned with respect to the size of the parts so as to effect a pressure change in the passage dependent upon the presence or absence of a part from the discharge portion thereof.
